UNITED STATES PATENT OFFICE.

BENJAMIN ROSENBERG, OF NEW YORK, N. Y.

COMBINED INSOLE AND SHANK.

1,118,151.

Specification of Letters Patent.

Patented Nov. 24, 1914.

Application filed August 5, 1914. Serial No. 855,169.

To all whom it may concern:

Be it known that I, BENJAMIN ROSENBERG, a citizen of the United States, and a resident of New York, borough of Brooklyn, county of Kings, and State of New York, have invented a certain new and useful Improvement in Combined Insoles and Shanks, of which the following is a full, clear, and exact specification.

10 This invention relates to a class of devices adapted to be used in conjunction with foot-wear worn by persons.

In accordance with the present methods employed in the manufacture of footwear particularly such forms as are commonly known as "turned" shoes the upper and sole of each shoe are lasted inside-out, and when the sole is stitched to the upper a marginal flange, or free edge is formed which overlaps the sole interiorly of the shoe when it is "turned" for receiving its finishings. When this type of shoe is worn the marginal free edge of the upper tends to absorb moisture which frequently causes it to curl in an upward direction interiorly of the shoe while drying, and if the shoe is not worn regularly the curling of the marginal free edge often becomes so pronounced as to make the shoe practically worthless after a 30 period of wear.

My invention has for its object primarily to overcome these objections by providing a combined insole and shank wherein is employed a flexible supporting plate, or layer 35 of leather, or the like of a form conforming to the shape of the inner bottom of the shoe so as to overlap the marginal free edge of the upper, and part of the heel portion of this supporting layer is split longitudinally. 40 to provide two superposed layer portions while part of the underside of the toe portion of the layer is cut away longitudinally. On the underside of the cutaway toe portion of the layer is provided a filler of cork, 45 or other non-absorbent material, and between the two superposed heel portions of the supporting layer is another filler of cork, or other non-absorbent material. These fillers are thereby spaced apart to prevent all 50 tendency to break, or split by the bending of the shoe when worn as is incident to shoes having cork insoles which embrace the greater part, or all of the interior of the shoe. Both fillers of cork are of forms 55 forming to the shapes of their respective parts of the supporting layer, and the up-

per surface of the curved edge of each filler is beveled to allow the beveled edges to be disposed between the sole of the shoe and the marginal free edge of its upper. In this 60 manner the supporting layer of the insole will rest on the top surface of the marginal free edge of the upper.

Another object of the invention is to form in the underside of each of the cork fillers 65 one, or a number of spaced transverse grooves to provide passages through which air may circulate to and under the marginal free edge of the upper so that the underneath surface of this free edge will be kept 70 dry, and should the edge tend to curl its course will be downwardly instead of upwardly; and a further object of the invention is to provide a metal shank which is rigidly held to a leather plate, or layer 75 secured to the underside of the insole.

A practical embodiment of the invention is represented in the accompanying drawing forming a part of this specification in which similar characters of reference indicate corresponding parts in all the views, the said invention being more fully described herein-after, and then pointed out in the claims at the end of the description.

In the drawing, Figure 1 is a perspective 85 view of a form of turned-shoe showing the sole stitched thereto before it is turned inside-out. Fig. 2 is a view showing the top of one form of combined insole and shank embodying my invention. Fig. 3 is a section 90 taken longitudinally through the shank. Fig. 4 is an inverted plan of the filler used in the toe portion of the insole. Fig. 5 is an inverted plan of the filler used in the heel portion of the insole. Fig. 6 is an edge view 95 of the toe filler. Fig. 7 is an edge view of the heel filler, and Fig. 8 is an inverted plan of the shank and its supporting plate used in conjunction with the insole.

The combined insole and shank has a supporting plate, or layer 10 which may be made of leather, or other flexible material, and this supporting layer is designed to conform with the shape of the interior of the shoe to which it is applied, the device being 100 especially adaptable to types of footwear commonly known as "turned" shoes, as shown at 11, which are made by stitching the sole 12 to the upper 13 and lasting these parts of the shoe inside-out. When the shoe 105 is turned to receive its finishings a marginal flange, or free edge, as 14, is formed, and

this free edge overlaps the sole interiorly of the shoe.

The supporting plate, or layer 10 is made of a size to rest on the marginal free edge 14, and this layer is preferably of a greater thickness than the insoles of the usual makes of shoes. The heel portion of the supporting layer 10 is longitudinally split to provide two superposed portions 15 and 16, and the underside of the toe portion of the supporting layer is cut away, at 17, longitudinally thereof. Between the superposed heel portions 15 and 16 is a filler 18 of cork, or other material which is a non-absorbent of moisture, and on the underside of the cut-away toe portion is a second filler 19 also of cork, or other material which is a non-absorbent of moisture.

The non-absorbent fillers 18 and 19 conform to the shape of the portions of the supporting layer 10 to which they are applied, but the fillers are of slightly less width than the supporting layer so that the supporting layer overhangs the fillers. The upper surface of the curved edge of each of the fillers 18 and 19 is beveled, at 20, and one or both surfaces of the entire body of each filler is tapered toward its straight edge so that the opposed ends thereof are graduated to nothing. When applied to the supporting layer both of the fillers 18 and 19 are spaced apart to obviate all tendency to break, or split by the bending of the shoe when worn as is incident to shoes having cork insoles covering the greater part, or all of the sole interiorly of the shoe, the well known brittleness of cork serving to make insoles of this class in ordinary use susceptible of being easily damaged. In the underside of each of the fillers 18 and 19 are a number of spaced transverse grooves 21 and 22, to provide passages whereby air may pass therethrough to and under the marginal free edge 14 of the upper of the shoe, as will be hereinafter more fully explained.

Secured by pasting, or otherwise to the underside of the supporting layer 10 is a shank plate 23 which is made preferably of leather, and this shank plate is of a length to extend from the end of the heel portion of the supporting layer to some distance of the foot portion thereof. On the underside of the shank plate 23 is fastened by pins, or the like a strip of steel, or other metal, as 24. The strip 24 extends from the central part of the heel part of the plate 23 to nearly the end of the plate which is under the foot portion of the supporting layer, and this strip is formed so that its central part is upwardly curved for likewise curving and stiffening the shank part of the insole as well as forming the insole in proper shape.

When the device is applied to the shoe after it is "turned" it is disposed interiorly of the shoe, and the beveled edges of the

non-absorbent fillers 18 and 19 are inserted under the marginal free edge 14 of the upper of the shoe. As these fillers are of less width than the supporting layer 10 as well as being of less width than the interior of the shoe, a space will be provided between the fillers and the upper under its marginal free edge. This space will thereby communicate with the grooves 21 and 22 of the fillers so that air will circulate under the marginal free edge of the upper for serving to keep the underneath surface thereof dry, and should this edge tend to curl its course will be downwardly instead of upwardly. The edge of the supporting layer 10 is then pasted, or otherwise secured on the top of the marginal free edge 14 of the upper. In this manner my combined insole and shank will greatly enhance the durability of "turned" shoes, and also render much comfort to the wearer.

In the foregoing description, I have embodied the preferred form of my invention, but I do not wish to be understood as limiting myself thereto as I am aware that modifications may be made therein without departing from the principle, or sacrificing any of the advantages of this invention, therefore I reserve to myself the right to make such changes as fairly fall within the scope of the appended claims.

Having thus described my invention, I claim as new and desire to secure by Letters Patent:—

1. In a combined insole and shank, adapted to be applied interiorly of a shoe having on its upper a marginal free edge overlapping the inner surface of the sole of the shoe, a flexible supporting layer conforming to the shape of the interior of the bottom of the shoe so as to be disposed on the top of the marginal free edge, and a non-absorbent filler on the bottom of the toe portion of the supporting layer, said filler being adapted to be inserted between the marginal free edge of the upper and the sole of the shoe, and the filler being of less width than the shoe to provide a space for the circulation of air under the marginal free edge of the upper, said filler being constructed on its underside with an air passage communicating with the air space under the marginal free edge of the upper, substantially as set forth and for the purpose specified.

2. In a combined insole and shank, adapted to be applied interiorly of a shoe having on its upper a marginal free edge overlapping the inner surface of the sole of the shoe, a flexible supporting layer conforming to the shape of the interior of the bottom of the shoe so as to be disposed on the top of the marginal free edge, and a non-absorbent filler on the bottom of the toe portion of the supporting layer, said filler having its side and toe edges beveled for

insertion between the marginal free edge of the upper and the sole of the shoe, and the filler being of less width than the shoe to provide a space for the circulation of

5 air under the marginal free edge of the upper, said filler being constructed on its underside with an air passage communicating with the air space under the marginal free edge of the upper, substantially as set forth and for the purpose specified.

3. In a combined insole and shank, adapted to be applied interiorly of a shoe having on its upper a marginal flap.

15 on its upper a marginal free edge overlapping the inner surface of the sole of the shoe, a flexible supporting layer conforming to the shape of the interior of the bottom of the shoe so as to be disposed on the top of the marginal free edge, a

top of the marginal free edge, a non-absorbent filler on the bottom of the toe portion of the supporting layer, said filler being adapted to be inserted between the marginal free edge of the upper and the sole of the shoe, and the filler being of less width than the shoe to provide a space for the air

25 than the shoe to provide a space for the circulation of air under the marginal free edge of the upper, said filler being constructed on its underside with an air passage communicating with the air space under the marginal free edge of the upper.

30 and a curved metal strip rigidly held on the shank portion of the underside of the supporting layer, substantially as set forth and for the purpose specified.

4. In a combined insole and shank, adapted to be applied interiorly of a shoe having on its upper a marginal flange.

on its upper a marginal free edge overlapping the inner surface of the sole of the shoe, a flexible supporting layer conforming to the shape of the interior of the bottom of the shoe so as to be disposed on the top of the marginal free edge, and a

of the marginal free edge, and a non-absorbent filler on the bottom of the heel portion of the supporting layer, said filler being adapted to be inserted between the marginal free edge of the upper and the

45 marginal free edge of the upper and the sole of the shoe, and the filler being of less width than the shoe to provide a space for the circulation of air under the marginal free edge of the upper, said filler being

50 free edge of the upper, said inner being constructed on its underside with an air passage communicating with the air space under the marginal free edge of the upper, substantially as set forth and for the purpose specified.

pose specified.

5. In a combined insole and shank, adapted to be applied interiorly of a shoe having on its upper a marginal free edge overlapping the inner surface of the sole of the shoe, a flexible supporting layer conform-

60 shoe, a flexible supporting layer conforming to the shape of the interior of the bottom of the shoe so as to be disposed on the top of the marginal free edge, a non-absorbent filler on the bottom of the heel portion of the supporting layer, said filler be-

65 tion of the supporting layer, said filler being adapted to be inserted between the mar-

ginal free edge of the upper and the sole of the shoe, and the filler being of less width than the shoe to provide a space for the circulation of air under the marginal free edge of the upper, said filler being constructed 70 on its underside with an air passage communicating with the air space under the marginal free edge of the upper, and a curved metal strip rigidly held on the shank portion of the underside of the supporting 75 layer, substantially as set forth and for the purpose specified.

ing to the shape of the interior of the bottom of the shoe so as to be disposed on the top of the marginal free edge, and two 85 spaced non-absorbent fillers on the bottom of the supporting layer, one at the

of the supporting layer, one at the toe portion and the other at the heel portion thereof, said fillers being adapted to be inserted between the marginal free edge of the upper 90 and the sole of the shoe, and both fillers be-

ing of less widths than the shoe to provide spaces for the circulation of air under the marginal free edge of the upper, said fillers being constructed on their undersides with 95 air passages communicating with the in-

air passages communicating with the air spaces under the marginal free edge of the upper, substantially as set forth and for the purpose specified.

... in a combined insole and shank, adapted to be applied interiorly of a shoe having on its upper a marginal free edge overlapping the inner surface of the sole of the shoe, a flexible supporting layer conforming to the shape of the inner surface of the sole.

ing to the shape of the interior of the bottom of the shoe so as to be disposed on the top of the marginal free edge, two spaced non-absorbent fillers on the bottom of the supporting layer, one at the toe portion 105

supporting layer, one at the toe portion and the other at the heel portion thereof, 110 said fillers being adapted to be inserted between the marginal free edge of the upper and the sole of the shoe, and both fillers be-

ing of less widths than the shoe to provide spaces for the circulation of air under the 115 marginal free edge of the upper, said fillers being constructed on their undersides with air passages communicating with the

air passages communicating with the air spaces under the marginal free edge of the upper, and a curved metal strip rigidly held on the shank portion of the underside of the supporting layer, substantially as set forth and for the purpose specified.

125
8. In a combined insole and shank, adapted to be applied interiorly of a shoe having on its upper a marginal free edge overlapping the inner surface of the sole of the

the shoe, a flexible supporting layer conforming to the shape of the interior of the bottom of the shoe so as to be disposed on the

top of the marginal free edge, and the heel of the supporting layer being longitudinally split to provide two superposed layers, a non-absorbent filler between the superposed layers, a second non-absorbent filler on the bottom of the toe portion of the supporting layer, said fillers being adapted to be inserted between the marginal free edge of the upper and the sole of the shoe, and both fillers being of less widths than the shoe to provide spaces for the circulation of air under the marginal free edge of the upper, said fillers being constructed

on their undersides with air passages communicating with the air spaces under the 15 marginal free edge of the upper, and a curved metal strip rigidly held on the shank portion of the underside of the supporting layer, substantially as set forth and for the purpose specified. 20

This specification signed and witnessed this fourth day of August A. D. 1914.
